SPOOL HOLDER UNIT

William E. Taylor, Riverside, Conn., assignor to
 American Can Company, New York, N. Y., a
 corporation of New Jersey

Application June 8, 1940, Serial No. 333,539

5 Claims. (Cl. 206—52)

The present invention relates to a spool assembly unit for adhesive tape or the like and has particular reference to a spool and housing arrangement wherein the spool is free to rotate within the housing to permit easy withdrawal of the tape through an opening or window formed in the spool housing.

An object of the invention is the provision of a spool assembly for tape and the like in which the protecting housing for the tape need not be removed when the tape is to be used and which by reason of the improved mounting of the tape spool containing the tape, the spool being freely rotatable in the housing, permits easy withdrawal of the tape as required from an opening cut through the housing wall.

Another object of the invention is the provision of such a spool assembly in which the rotatable mounting of the spool of tape is made without the use of extra parts, a simple spool being so shaped as to be freely rotatable directly on shaped parts of the housing, the structure also allowing for closing of the opening in the housing and for holding the free end of the tape in position where it is easily accessible when the housing is to be opened for dispensing of the tape.

Numerous other objects and advantages of the invention will be apparent as it is better understood from the following description, which, taken in connection with the accompanying drawing, discloses a preferred embodiment thereof.

Referring to the drawing:

Figure 1 is a combination side elevation and sectional view of the spool holder unit illustrating parts broken back and showing portions of the unit with a roll of tape in section;

Fig. 2 is a top plan view of the unit partly broken back with parts shown in section;

Fig. 3 is an enlarged sectional detail of the upper corner of the unit as taken substantially along the line 3—3 in Fig. 2; and

Fig. 4 is an enlarged sectional detail showing the rotatable connection between the spool and the housing, as viewed along the line 4—4 in Fig. 1.

As an example of the invention the drawing illustrates a cylindrical spool or core member 11 on which tape 12 may be wound. Such a spool is confined within a cylindrical housing comprising a body 13 and ends 14. The body 13 (Fig. 3) is permanently united to each end 14 in a double seam 15. Each end 14 is formed

with a central countersunk section 16 which is of smaller diameter than the inner chuck wall 17 of the end, the latter providing for the double seam connection 15 in the usual manner.

5 The outer diameter of the countersunk section 16 is spaced inwardly from the body wall 13 of the housing when the parts are in seamed position, as best illustrated in Fig. 3. The housing 13 is cut along one side to provide an opening 10 or window 21 through which the tape 12 is withdrawn as used. The side edges of the window 21 are bent back in hemmed edges 22. Similar hemmed edges 23 are formed at the top and the bottom adjacent the ends 14. This provides a 15 smooth boundary or surrounding edge for the opening of the window 21.

Provision is made for closing off this window and completely confining the tape 12 which is wound on the spool 11, when the spool holder unit is used to protect the tape and keep it in proper condition. For this purpose a sliding curved gate 25 is used and this gate is disposed inside of the curved wall of the housing body 13. The upper and lower edges of the gate 25 are 20 slidingly held as at 26 (Fig. 3) between the wall of the housing 13 and the outside wall of the central countersunk sections 16 of the two end members 14. This location of the ends of the gate allows for free sliding movement along the 25 inside wall of the housing and confines the gate to a circular path of travel, the outer surface of the gate fitting snugly against the housing wall in all positions.

The gate 25 is moved from its open position 30 (illustrated in Figs. 1 and 2) where the major part of the window 21 is exposed, into a closed position where the entire window is covered over. A finger engaging rib 27 is formed in the wall of the gate 25 adjacent one vertical edge 35 and allows for easy manual manipulation of the gate to slide it into open or closed position as desired.

The tape 12 is withdrawn through the open 40 window 21 as illustrated in Fig. 2. The window at such time is open and the gate 25 is pushed back behind the housing wall where the major 45 part of the opening is exposed. After the desired amount of tape has been withdrawn and the end of the tape has been cut off, the gate is slid into closed position. This confines the tape 50 within the housing. In its closed position the forward edge of the gate 25, which is hemmed inwardly as illustrated at 28 in Fig. 2, engages 55 against the tape and the end of the tape is thus

clamped between the gate edge and that part of the wall of the housing 13 which is adjacent one of the vertical hemmed edges 22. The tape is held in such position as long as the housing is closed and it can be easily grasped when the gate is slid back for the next withdrawal of the tape.

In this withdrawal of the tape it is not necessary to take the housing unit apart as is usual in containers of this sort. The free rotation of the spool 11 with the roll of tape, within the spool holder, makes this possible. As to this rotative construction, the spool 11 at each end is bent outwardly to provide an annular curved trough 31 (Fig. 4). The central part of each end member 14 is provided with an opening 32 which is surrounded and bounded by an inwardly curled edge 33. This curled edge on each end of the unit fits into its cooperating spool trough 31. The two ends 14 are of the same construction and this provides a freely rotatable connection between the spool ends and the end members of the holder unit.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A spool assembly unit comprising a tubular housing having a window on one side, end members double seamed to said housing, each member being countersunk inside of its double seamed joint to provide a space between it and the wall of said housing, a sliding gate located inside of said housing and having its opposed ends movably confined within the said spaces between the housing and said end members so that the gate may be drawn across said housing window to close the housing, and a cylindrical spool located inside of said housing having its ends rotatably connected with said housing end members to adapt the unit for easy withdrawal of tape wound on said spool where the free end of the tape passes through said window when said sliding gate is in open position, said sliding gate when in closed position lapping inside of an edge of the housing at one side of said window to hold the free end of the tape between withdrawals from the spool unit.

2. A spool assembly unit comprising a tubular housing having a window along one side, end members permanently secured to the ends of said housing, said end members being centrally apertured with the material of the members rolled inwardly to form curved bearing surfaces, and a cylindrical spool located in said housing and having in its ends concave bearing surfaces rotatably mounted on the bearing surfaces of said end members and extending parallel with said housing window to adapt the unit for easy withdrawal of tape wound on said spool where the free end of the tape passes through said window

so that as the tape is withdrawn said spool rotates to supply more of the tape for passage through said housing window.

3. A spool assembly unit comprising a tubular housing having a window along one side, end members permanently secured to the ends of said housing, each member having a circular opening cut centrally of its wall which is curled inwardly in that region to provide a surrounding open curl edge for the opening and an inwardly directed annular bearing surface, and a cylindrical spool having its ends curled to form annular troughs rotatably connected in said housing in position to extend parallel to said housing window, each open annular curl of said end members having its annular bearing surface extending into a said annular trough of the adjacent end of said spool to provide said rotatable connection to adapt the unit for easy withdrawal of tape wound on said spool where the free end of the tape passes through said window so that as the tape is withdrawn said spool rotates to supply more of the tape for passage through said housing window.

4. A spool assembly unit comprising a cylindrical housing having a window opening therein, end members secured to opposite ends of said housing, each of said end members being provided with a central aperture defined by an inwardly and thence outwardly extending curled edge of said end member to constitute an annular bearing surface, and a tape carrying cylindrical spool disposed within said housing and having its opposite ends extending radially outwardly and thence axially in an annular curved trough rotatably engaging said bearing surface of the housing end members, whereby said spool rotates relative to said housing when the tape carried thereby is drawn through said housing opening.

5. A spool assembly unit comprising a cylindrical housing having a window opening therein, countersunk end members permanently secured to opposite ends of said housing in seamed joints, the inner portion of the annular countersunk wall of each end member being inwardly offset to provide an annular bearing seat spaced from the inner wall of said housing, each of said end members being provided with a central aperture defined by an inwardly and thence outwardly extending curled edge of said end member to constitute an annular bearing surface, an arcuate gate member movably mounted within said housing, the opposite ends of said gate member being confined between said housing and said end members in sliding engagement with said inwardly offset end member bearing seats so that said gate member may be moved relative to said housing to open and close said housing opening, and a tape carrying cylindrical spool disposed within said housing and having its opposite ends extending radially outwardly and thence axially in an annular curved trough rotatably engaging said bearing surface of the housing end members, whereby said spool rotates relative to said housing when the tape carried thereby is drawn through said housing opening.

WILLIAM E. TAYLOR.
